CABLE BRACE

Robert A. Potruch, Miami Beach, Fla., assignor to Lumidor Products Corporation, Hialeah, Fla., a corporation of Maryland

Filed Sept. 5, 1963, Ser. No. 76,491

Term of patent 14 years

(Cl. D26—10)

FIGURES 3 and 4 are top and bottom plan views respectively.

I claim:

The ornamental design for a cable brace, substantially as shown and described.
